UNITED STATES PATENT OFFICE.

JOHN F. SULLIVAN, OF SAN FRANCISCO, CALIFORNIA.

COMBINATION GAS AND COAL RANGE.

Application filed September 5, 1922. Serial No. 586,104.

To all whom it may concern:

Be it known that I, JOHN F. SULLIVAN, a citizen of the United States, residing at the city and county of San Francisco and State of California, have invented certain new and useful Improvements in Combination Gas and Coal Ranges, of which the following is a specification.

My invention relates to that class of cook-stoves or ranges which, from their adaptability for the use of gaseous or solid fuel, have come to be known as combination gas and coal ranges.

One object of my invention is to incorporate the coal-heat member of the combination in a position relatively to the gas-heat members, which will not only give full play and effect to its functions in cooking, heating the kitchen, and consuming garbage, but also will confine the whole structure within reasonable dimensions.

Another object of my invention is to provide for a sufficiently effective heat presentation of the coal heat member, at the same time providing for a more perfect combustion of its fuel.

Another object is to better adapt the broiler and oven members subject to gas heat, for conjoint use with the coal-heat member, or for the independent use of either, by means for properly controlling the communication between the broiler and oven members.

Another object is to provide for an effective discharge of the gas fumes from the oven member.

With these objects in view, my invention consists in the novel combination gas and coal range which I shall now fully describe by reference to the accompanying drawings, in which—

Fig. 1 is a front view of my range partly in elevation and partly in vertical section.

Fig. 2 is a horizontal section on the line 2—2 of Fig. 1.

Fig. 3 is a horizontal section on the line 3—3 of Fig. 1.

Fig. 4 is a horizontal section, partly broken on the line 4—4 of Fig. 1.

Fig. 5 is a front elevation of the members shown in section in Fig. 1.

Fig. 6 is a section on the line 6—6 of Fig. 5.

Fig. 7 is a vertical section through the stove-pipe and the members adjacent thereto at the back of the range.

Referring to Fig. 1, the numeral 1 indicates the main top, 2 the high shelf, 3 the broiler with its pan 3' and 4 the oven of a common type of gas range. Incorporated in the general frame of the range and directly underlying the broiler 3 is a coal-heater member indicated as a whole by 5, and comprising a grate 6, an ash-pit 7 and a top plate 8. The grate 6 underlies the outer section area of the bottom of the broiler, and the top plate 8 underlies and is spaced from the inner section area of said broiler bottom and extends to and is closed in by the wall of the broiler structure extended downward, all as clearly shown in Fig. 1. At the back end of the space between the top plate 8 and the broiler bottom there is a damper 9, Fig. 7, operated by a rod 10, Fig. 4, and controlling the communication of said space with the stove pipe 11 to the chimney, and in said space there may be fitted a deflector plate 8'—Figs. 4 and 1, for the products of combustion.

It will now be seen that the products of combustion from the fuel in the coal heater 5 are not circulated in an extensive path about the other members of the range as is common in the art but pass directly to the stove pipe as indicated by the arrows in Fig. 4. Combustion is thus not retarded and is relatively complete so that smoke and soot are reduced to a minimum. The heat from the combustion of fuel, such as coal, wood, or garbage, in the member 5, is utilized for heating the chamber 3 which when gas alone is used is the broiler chamber, but which when used with the heat from member 5 may be used as an oven and this heat is directed wholly by radiation through the bottom of the chamber 3. And, moreover, the member 5 is adapted for the desirable functions of a kitchen heater and a garbage incinerator. Its location below the broiler is also of advantage in that it keeps the whole range within a relatively short length, as seen in Fig. 1.

In order to feed the heater 5, there may be a pouch feed through the door 12, and in addition thereto the outer section of the bottom of the broiler lying above the grate or

fire box 6 is made as a separate plate 13, Figs. 1, 4 and 6, which may be lifted as shown by the dotted lines in Fig. 6, and supported upon a lug 14, so that by opening the 5 broiler door, and lifting the plate 13, the fire box is exposed to permit the dumping into it of larger fuel. The plate 13 may have griddles 15, as shown in Figs. 4 and 6. The broiler 3, as seen in Figs. 1 and 6 has 10 the usual gas burners 16, and said broiler and the oven 4 communicate through the usual side openings 17, Fig. 1.

When the coal heater 5 is used the oven 4 may be used as a warming chamber, deriving 15 a modicum of heat from the broiler chamber. But in most cases, in order to confine the heat to the latter chamber when the coal heater is used, it is best to cut out the oven 4 entirely, and for this purpose I 20 have the damper slides 18, Figs. 1 and 3, which are adapted to close and open the communications 17, said slides being operated by a sliding rod 19 and parallel side links 20.

25 Air is supplied to the gas heated chambers through the usual holes 21, in the doors. Fig. 5.

The gas fumes from the oven rise to the 30 openings 22 in the upper lining of the oven at the back, Figs. 2 and 6, and thence pass forwardly between the top lining and the top plate of the oven, to the front, as indicated by the arrows in Fig. 2. Thence they 35 pass through openings 23 into inclined flues 24, Figs. 2, 6 and 7, formed in the sides at the top of the oven and thence to a top flue 25 at the back—Fig. 2, which flue communicates by a short pipe section 26 with the stove pipe to the chimney, as seen in Fig. 2.

40 The range may operate solely with gas, or with such fuel as coal, wood or garbage, or both forms of fuel may be used together.

Although I have herein entitled my improved range, and described and claimed the 45 same in terms of gas heat as the principal source, associated with coal heat, it is to be understood that my invention is equally applicable to a range in which the chief heat is electric, the electric heating elements being, 50 as far as the combinations described and claimed are concerned, the equivalents of the gas burners, and are so herein contemplated.

I claim:—

1. A combination gas and coal range comprising a main top; a broiler at one end of the main top; suitable heating elements for the main top and broiler; and a coal heater underlying and adjoining the broiler, the bottom of the broiler forming the immediate 60 and sole cover of the coal heater and uninterrupted exposure to the products of combustion of the fuel in said heater.

2. A combination gas and coal range comprising a main top; a broiler at one end of 65 the main top; suitable heating elements for

the main top and broiler; and a coal heater underlying the broiler, the bottom of the broiler being directly exposed to the products of combustion of the fuel in the coal heater, and said broiler bottom having a 70 movable section to afford fuel-feed access to the coal heater through the broiler.

3. A combination gas and coal range comprising a main top; a broiler at one end of the main top; suitable heating elements for 75 the main top and broiler; and a coal heater underlying the broiler, the bottom of the broiler being directly exposed to the products of combustion of the fuel in the coal heater, and said broiler bottom having a 80 movable section to afford fuel-feed access to the coal heater through the broiler, said movable section being provided with griddles.

4. A combination gas and coal range comprising a main top; a broiler at one end of 85 the main top; an oven above and communicating with the broiler; a damper for controlling said communication; suitable burners for the main top and broiler; and a coal heater underlying the broiler, the bottom of 90 the broiler being directly exposed to the products of combustion of the fuel in the coal heater.

5. A combination gas and coal range comprising a main top; a broiler at one end of 95 the main top; suitable heating elements for the main top and broiler; a coal heater underlying and adjoining the broiler; the bottom of the broiler forming the immediate and sole cover of the coal heater and uninterrupted exposure to the products of combustion of the fuel in said heater, said bottom being raised above the coal heater to provide an escape flue for said products of combustion; and a stove pipe into which the 100 products of combustion directly pass from and at the level of said escape flue.

6. A combination gas and coal range comprising a main top; a broiler at one end of the main top; an oven above and communicating with the broiler; a damper for controlling said communication; suitable burners for the main top and broiler; a coal heater underlying and adjoining the broiler, the bottom of the broiler forming the immediate and sole cover of the coal heater and uninterrupted exposure to the products of combustion of the fuel in said heater, said bottom being raised above the coal heater to provide an escape flue under said bottom for 110 said products of combustion; and a stove pipe into which the products of combustion directly pass from and at the level of said escape flue.

7. A combination gas and coal range comprising a main top; a broiler at one end of the main top; suitable heating elements for the main top and broiler; a coal heater underlying the broiler, the bottom of the broiler being directly exposed to the products of 120

- combustion of the fuel in the coal heater and spaced from the top of said heater to provide an escape flue under said bottom for said products of combustion, and said broiler bottom having a movable section to afford fuel-feed access to the coal heater through the broiler; and a stove pipe into which the products of combustion directly pass from said escape flue.
- 10 8. A combination gas and coal range comprising a main top; a broiler at one end of the main top; an oven above and communicating with the broiler; a damper for controlling said communication; suitable gas 15 burners for the main top and broiler; a coal heater underlying the broiler, the bottom of the broiler being directly exposed to the products of combustion of the fuel in the coal heater, and spaced from the top of said 20 coal heater to provide an escape flue under said bottom for said products of combustion; a stove pipe into which the products of combustion directly pass from said escape flue; and means for conducting the gas 25 fumes from the oven forwardly above its top

and thence backwardly along its sides to the stove pipe.

9. A combination gas and coal range comprising a main top; a broiler at one end of the main top; an oven above and communicating with the broiler; suitable gas burners for the main top and broiler; a coal heater underlying the broiler, the bottom of the broiler being directly exposed to the products of combustion of the fuel in the coal 35 heater and spaced from the top of said heater to provide an escape flue under said bottom for said products of combustion, and said broiler bottom having a movable section to afford fuel feed access to the coal heater 40 through the broiler; a stove pipe into which the products of combustion directly pass from said escape flue; and means for conducting the gas fumes from the oven forwardly above its top and thence backwardly 45 along its sides to the stove pipe.

In testimony whereof I have signed my name to this specification.

JOHN F. SULLIVAN.
